UNITED STATES PATENT OFFICE.

ALEXANDER P. MORROW, OF ELMIRA, NEW YORK.

DESIGN FOR A BICYCLE-HUB.

SPECIFICATION forming part of Design No. 32,234, dated February 13, 1900.

Application filed January 13, 1900. Serial No. 1,394. Term of patent 14 years.

To all whom it may concern:

Be it known that I, ALEXANDER P. MORROW, a citizen of the United States, residing at Elmira, in the county of Chemung and State 5 of New York, have invented and produced a new and original Design for Bicycle-Hubs; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My invention is a design for bicycle-hubs; and it consists of a hub having the novel shape and contour shown in the accompanying drawings, in which—

Figure 1 is a view in perspective of the hub 20 embodying the design. Fig. 2 is a perspective view taken from the end opposite to that shown in Fig. 1, and Fig. 3 is a side elevation.

The reference-numeral 1 designates the sleeve or body portion of the hub, having adjacent to one end thereof a vertical flange 2, 25 formed with an annular row of perforations 3 and terminating at the outer side of said flange 2 in a horizontal portion 4.

5 designates a hollow bell-shaped flange overhanging the sleeve or body portion 1 of 30 the hub and separated from the vertical flange 2 by a horizontal portion 6. The outer end or rim of the bell-shaped flange terminates in a vertical annular flange 7, formed with a row of perforations 8.

35 The leading features of my design are the hollow bell-shaped flange 5 overhanging the sleeve 1 and having the annular vertical rim 7, together with the horizontal surface 6.

Minor features of the design are the sleeve 40 or body portion of the hub extending beyond and concentric to the hollow overhanging flange 5, the perforated vertical flange 2, and the horizontal surface 4.

I claim—

45 The design for a bicycle-hub herein shown and described.

In testimony whereof I affix my signature in presence of two witnesses.

ALEXANDER P. MORROW.
